Application filed May 6, 1929. Serial No. 360,833.

UNITED STATES PATENT OFFICE

JAMES M. OBERTI, OF SAN FRANCISCO, CALIFORNIA

FLOOR SQUEEGEE

Application filed May 6, 1929. Serial No. 360,833.

My invention relates to improvements in floor squeegees, and it consists in the combinations, constructions and arrangements hereinafter described and claimed.

An object of my invention is to provide a floor squeegee that is an improvement over the form of the device shown in my Patent No. 1,497,933, issued June 17, 1924. In the patent I show a frame having a concave bottom edge and a rubber member having a convex upper edge, the rubber member being received within the frame.

I have found that by inclining the frame from the vertical so as to incline the rubber, it is not necessary to provide the frame and the rubber with concave and convex edges. The slanting of the rubber permits its lower edge to fill any irregularities in the floor just as effectively as accomplished by the patented device. At the same time, the device can be manufactured more cheaply. It is efficient also for sweeping the floors in place of the hair brush.

A further object of my invention is to provide a device of the type described which is extremely simple in construction and durable and efficient for the purpose intended.

Other objects and advantages will appear as the specification proceeds, and the novel features will be particularly pointed out in the appended claims.

My invention is illustrated in the accompanying drawing, in which

Figure 1 is a top plan view of the device;
Figure 2 is a front elevation;

Figure 3 is a section along the line 3—3 of Figure 1;

Figure 4 is a perspective view of one end of the device, and

Figure 5 is a sectional view through a modified form of the device.

In carrying out my invention I provide a channel-shaped frame 1 (see Figure 3) that is curved in the manner shown in Figure 1. Within the frame I dispose a channel-shaped holder 2. This holder carries two strips of rubber 3 and 4. The strip 3 is of a narrower width than the strip 4 and projects a less distance below the bottom of the frame 1 than does the strip 4.

It will be noted from Figure 3 that the sides 5 and 6 of the frame are inclined forwardly so as to incline the rubber strips 3 and 4. The holder 2 is clamped in the frame 1 by means of bolts 7. The bolts at the same time act as stops and limit the upward movement of the holder. It will be noted that since the frame is inclined forwardly throughout its length, its upper edge describes an arc having a smaller radius than the radius of the arc of the lower edge.

In Figure 4 I show one of the ends of the frame 1. This end has a piece 8 that is bent downwardly from the top and curved so as not to mar any object should the squeegee strike the same. A handle 9 is hinged to the frame 1 at 10 and is of a length sufficient to permit an operator to move the squeegee over a floor while the operator stands erect. If desired, the lower edges of the sides 5 and 6 may be crimped inwardly as shown at 11 and 12 for aiding in securing the holder 2 in place.

From the foregoing description of the various parts of the device, the operation thereof may be readily understood.

The squeegee is moved over the floor by merely pushing or pulling upon the handle 9. The curve of the frame 1 directs the water from the ends of the frame to the center. The frame extends a sufficient distance above the floor to prevent the water from flowing over the top of the frame. The angle at which the rubber strip 4 extends permits it to be flexed slightly when the squeegee is moved, and this flexing will cause the lower edge 13 of the strip 4 to conform to all irregularities in the floor surface. The strip 3 acts as a bracing member for the strip 4, and this strip will give slightly so as to provide a greater resiliency to the wider strip.

The squeegee is also efficient to sweep floors in place of hair brush, doing better sweeping than the brush because it removes the fine dust that the hair brush leaves on the floor.

In Figure 5, I show a modified form of squeegee in which the strips of rubber 3 and 4 are secured in a channel formed by two members 25 and 26. These members have longitudinal grooves 27 and 28 respectively in their outer faces, and the ridges formed by

the walls of the grooves abut one another and are secured together by bolts 29 or other suitable fastening means.

The tops of the members 25 and 26 are provided with flanges 30 and 31 that overlap each other, as is clearly shown. These flanges form a top to the device.

It is to be understood that the length of the members 25 and 26 is the same as the frame 1, and that these members are curved in the same manner.

Although I have shown and described two embodiments of my invention, it is to be understood that the same is susceptible of various changes, and I reserve the right to employ such changes as may come within the scope of the invention as claimed.

I claim:

1. A squeegee curved slightly in the direction of its length and having its upper edge describing an arc having a smaller radius than the radius of the arc for the lower edge, thus causing the squeegee to incline forwardly.

2. A floor squeegee comprising a frame of inverted U-shape in cross section and being curved slightly in the direction of its length and having its upper edge describing an arc having a smaller radius than the radius of the arc for the lower edge and flexible strips secured in said frame and being inclined in the same manner as the sides of the frame.

JAMES M. OBERTI.
